Primary Examiner — Susan E Krakower*Assistant Examiner* — Jerry Shiuan-Hua Hsu(74) Attorney, Agent, or Firm — Kacvinsky Daisak Bluni PLLC(57) CLAIM

The ornamental design for a cabin for automobile, as shown and described.

DESCRIPTION

FIG. 1 is a front view of the cabin for automobile, showing my new design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken lines illustrate portions of the cabin for automobile that form no part of the claimed design.
